UNITED STATES PATENT OFFICE

ALVA M. HULL, OF DETROIT, MICHIGAN, ASSIGNOR OF ONE-FIFTH TO FRANCIS D. HARDESTY AND FOUR-FIFTHS TO HARRY G. WESTFALL, TRUSTEE FOR NORMA M. HULL, THELMA M. HULL WESTFALL, AND MABEL G. PICKETT, ALL OF DETROIT, MICHIGAN

FIREPROOF BUILDING CONSTRUCTION

Application filed October 4, 1927. Serial No. 223,884.

The present invention relates to fire-proof buildings and specifically to the elements for producing such buildings.

Among the objects of the invention are means by which such buildings may be easily, quickly, and economically constructed.

Another object is means by which such buildings may be assembled permanently with the use of few tools and without alteration of parts.

Still other objects will readily occur to those skilled in the art upon reference to the following description and accompanying drawings in which:

5 Fig. 1 is a perspective view of a part of a completed frame-work of a building with parts of the walls, floors and roof finished;

Fig. 2 is a similar view showing a partition;

10 Figs. 3 and 4 are perspective views of wall units;

Figs. 5 is a view of a door unit;

Fig. 6 is another view of the same installed and partially finished;

15 Fig. 7 shows a window unit;

Fig. 8 shows the same in position and partially finished;

Fig. 9 is an enlarged view showing the means of forming a stud;

20 Fig. 10 is another view of the same disassembled;

Fig. 11 shows a corner unit;

Fig. 12 shows the same before assembly;

25 Figs. 13 to 16 show views of parts of the window and door units before assembly;

Fig. 17 shows a roof element; and

Figs. 18 to 21 show details of the rafter construction.

In the drawings, the house frame-work is shown as erected on a conventional masonry foundation 30 and provided with steel joists 31. The latter may be supported intermediate their ends by columns, if desired.

Upon the foundation is placed a metal channel 35 opening upward and in this channel are placed the wall and other units described more in detail below. Upon the tops of these units mentioned is another channel 35a of similar shape and size to channel 35 and this is secured to the wall and other

units either by bolting or spot welding. Upon the channels 35a in the form shown in Fig. 1, are then placed the ceiling joists 36 and the gable end wall units which latter are triangular in shape, where a blank wall 55 is desired.

Upon the channels 35a are also secured the lower ends of the rafters or roof supports 37 and secured at their lower ends by bolting. And upon the rafters 37 are bolted the tile 60 racks or frames 38 serving to support the tile or other roofing indicated at 39.

As shown in Fig. 1, the preferred form of the structure includes the securing to the outside and inside of the wall units, metal lath 40 upon which is applied the plaster, stucco, or other plastic wall surfacing 43 material, while a similar lath 41 is secured to the floor joists 31 and a plastic flooring material 42 applied thereto.

As stated above the blank wall units are shown more in detail in Figs. 3 and 4. These are designed to be standard units for a given height wall and are used in both outside walls and partitions. The forms shown in these two figures consist of rectangular frames of sheet metal channels 50 which are ribbed longitudinally as at 51 for the purpose of stiffening and to provide an air pocket when two units are placed together. The side channels are also provided with punched out tongues 52 which are pointed up on one side and down on the other, while the bottom and top channels are provided with keyhole slots 53. As indicated these units may be of different sizes if desired, and the wider ones provided with one or more central members 50a which are preferably of two channels 50, back to back and spot welded. These of course need not be slotted.

The wall units are preferably provided with a face covering on both sides of metal lath 54 stretched tightly and spot welded in place.

The door unit is shown in Figs. 5 and 6, the latter showing also portions of a finished door-frame.

In these figures a rectangular frame 60 similar to a wall unit is used. The side members are provided with similar tongues 52 100

and the top member with keyhole slots 63. The bottom member 64 however is somewhat different. This member has the side walls 65 cut and flattened inwardly for the greater part of its intermediate portion. A portion at each end, however, is left in shape so that another rectangular frame 66 may be constructed within the main frame. This frame 66 is shorter and narrower than frame 60 but is made of similar channel material. The bottom member is common to both and the top member of frame 66 consists of a channel 67 extending across frame 60 near the top thereof. While above member 67 the two frames are trussed as by the central upright short double channel 68 and the diagonals 69. The door unit, like the wall units, is provided with metal lath 70 on both faces over the space between the frames 60 and 66. It is preferred to weld these several parts together as in the wall units.

In addition to the features just mentioned the door unit is also provided at the top and sides with an L-section strip 71, welded to the channels 66, serving to locate the facing member 72 and as a guide for plastering.

Figure 13 shows in disassembled relation coacting parts of the several components of a door-frame.

30 The window unit is shown in detail in Figs. 7 and 8, and 14 to 16 inclusive.

This unit consists of an outer frame 80, similar in all respects to a wall unit, having an upper cross member 81 near its top, trussed as in the case of member 67 of the door-frame. Near the bottom also is fixed a cross member 82 additionally supported centrally by a double channel 83.

The window unit is likewise provided with 40 an inner frame 85 consisting of two uprights 86 extending between and secured to cross members 81 and 82 at a suitable distance from the sides of the frame 80 and between the members 86 are fixed cross members 87, 45 the members 86 and 87 being of proper lengths to locate the included rectangle at the desired position and make it of a size suitable for a window of the desired size. The members 86 and 87 in the form shown, are of less 50 width than the channel members forming the outer frame and cross members 81 and 82 and are so placed that they align with the inner face of the outer frame 80. The members 87 are provided with the spacing L-section 55 pieces 88 as in the door units but these pieces 88 are provided with tapped holes 89 for the purpose of receiving the window frame screws. Also, members 86 are provided on their inner edges with similar L-shaped irons

60 90, but instead of putting similar pieces on the outer side of members 86, strap or tie members 91 are used. These are short straps or bars having both ends bent at right angles and one end drilled and tapped. The un- 65 drilled end of piece 91 is welded to the outer

channel as shown in Figs. 7 and 8 and the drilled end is aligned with the face of part 86 and welded. These also serve to anchor the window frame. After these parts have been properly secured together, metal lath is 70 spot welded on the outer face over the spaces between members 81 and 82 and the top and bottom respectively. On the inside face the lath extends inwardly to members 87 and over the space between members 86 and the 75 side channels of the outer frame.

These units are designed for the reception of metal window frames and casements and stone facings and sills and Figs. 8 and 14 to 16 show the assembly of these parts.

80 The disassembled parts of one side of a window frame are shown in Fig. 16 in their relative locations, the stone-facing being shown at 92. A similar showing of the top of the window is shown in Fig. 14 with the 85 stone-facing indicated at 93. Likewise a similar showing of the lower side is shown in Fig. 15 with the stone sill indicated at 94.

In Fig. 8, the metal window frame is shown at 95 and the sash at 96.

90 A corner unit is shown in Figs. 11 and 12, and consists of a double channel 100 formed so as to be the same as two channels 50 secured at right angles. This double channel is of the same length as the other units, and 95 provided with tongues 52. In order to assure rigidity and fix the angular relation an angle iron 101 is fixed to member 100 by welding short bonds 102 to both members and so proportioning the parts that the unit is substantially a square with the angle iron 101 at one corner. The two open sides of the unit are covered with metal lath 103 as indicated.

95 The roofing unit or tile rack is shown in Fig. 17 and consists of a rectangular frame 105 of light sheet metal channel 110 of suitable length to extend from the center line of one rafter to the center line of another, preferably extending over one or two intermediate rafters. The width of the frame should be 110 such that a roofing tile will hook over one side and lie upon the other, or a multiple of such width. In the latter case, the frame will include longitudinal channels 111 dividing the frame equally. Fig. 17 shows such a multiple rack which may be considered either a single multiple rack or four racks grouped. In these racks it is preferred to tie the longitudinals together by a cross tie member 112, all of the parts being preferably 115 welded.

120 The racks may be secured to the rafters by suitable clamps or spot welded thereto and of course with the members 110 and 111 extending horizontally.

125 The form of rafter preferred is shown in Figs. 18 to 21. The rafter itself is preferably a sheet metal I-beam 120 and at the ridge of the roof the ends are preferably fastened together by welding inside the angle 130

an angular plate 121 with a similar but longer plate 22 on the outside of the angle. Fig. 21 shows two angular plates 123 for securing the lower ends of rafters 120 to the wall capping channels 35a.

It will be noted that the wall units of Figs. 3 and 4 are readily secured together by the tongues 52 as the abutting channel members are placed together as the tongues 52 on one unit readily enter the opening behind the tongue on the other. The same is true of the wall units and window, door, and corner units as all are provided with similar tongues so placed as to register properly.

15 It will also be noted that all units except the corners, having the keyhole slots 53 may readily be bolted to the members lying upon them at top or bottom.

While the several units are described above 20 as rectangular, it is, of course, obvious that in gable ends as shown in Fig. 1, triangular units must be used, window units for such places, if to be centered, should have a pointed upper end instead of that shown in Fig. 7. 25 In such window units, however, the members 86 and 87 and their supporting members may be the same.

Fig. 1 shows very clearly the construction 30 and relation of the parts in the outside walls of a building and also the roof construction.

Fig. 2 shows clearly the construction and relation of parts in the dividing walls and floors of such a building and it is not considered necessary to enter into further detail.

35 Now having described the invention and the preferred form of embodiment thereof it is to be understood that said invention is to be limited, not to the specific details herein set forth, but only by the scope of the 40 claims which follow.

I claim:—

1. Wall construction for fire-proof buildings comprising a channel member opening upwardly, a series of independent rectangular units abutting together in said channel and secured together by interlocking members, a second channel member extending over said series of units and secured thereto, and metal lath secured to the outer and inner 50 faces of said units.

2. A unit for wall construction for buildings, consisting of a frame made by securing together sheet metal channel members with their flanges extending inwardly, and securing to the two faces of said frame metal lath, the side members of said frame having punched out tongues of uniform size pointing down on one side member and up on the other side member, and the top and bottom 55 members being provided with a plurality of keyhole slots.

ALVA M. HULL.
